UNITED STATES PATENT OFFICE.

JACOB A. HYLE AND ROBERT A. THOMANN, OF ST. LOUIS, MISSOURI.

RAILWAY JOINT LOCK.

Application filed October 10, 1924. Serial No. 742,783.

To all whom it may concern:

Be it known that we, JACOB ALVIN HYLE and ROBERT A. THOMANN, citizens of the United States, residing in the city and county of St. Louis and State of Missouri, have invented certain new and useful Improvements in Railway Joint Locks, of which the following is a specification.

This invention relates to a new and novel improvement in railway joint locks.

The prime object of this invention is to provide simple, durable, economical, reliable and efficient means whereby the meeting ends of the track rails are always locked and retained in alignment under all conditions.

Another object of the invention is to provide novel means for automatically holding the meeting ends of railway rails securely together, and to take up the wear at that point and at the same time prevent the loosening of the bolts and nuts.

A further object of the invention is to so construct reliable and efficient means as to always secure and retain the meeting ends of the rails in firm connection to prevent pounding and clinking of the rolling stock as it passes over the joint, and thus materially prevent the wearing of the rails at the ends.

The foregoing and such other objects as may appear from the ensuing description are accomplished by the construction, arrangement, location and combination of the several parts hereinafter more fully described, illustrated in the accompanying drawings and particularly pointed out in the claims appended hereto, it being understood that slight changes in the precise proportions and minor details of the construction may be resorted to without departing from the spirit or sacrificing any of the advantages of the invention.

In the accompanying drawings forming a part of this specification it will be seen that:

Figure 1 is a side elevation of the improved means embodying our invention.

Figure 2 is a side elevation of our novel locking plate detached from the rails.

Figure 3 is a plan view of the plate shown 50 in Figure 2.

Figure 4 is a plan showing the locking plate secured in its normal position by the nuts and bolts, and showing one of the rail splice bars partly in section.

Figure 5 is a transverse section taken in the plane of the dotted lines 5—5, Fig. 1, looking in the direction of the arrows, and

Figure 6 is a transverse section taken in the plane of the dotted lines 6—6, Fig. 3, 60 looking in the direction of the arrows.

In the embodiment of our invention as illustrated, it will be seen that the numeral 1 designates the track rails, 2 the rail clamping or splice bars, each of said bars being 65 formed with four suitable central openings for the reception of the securing bolts 3, each bolt being passed through suitable openings formed through the track rails and said central opening on the bars, and securely fitted to the threaded end portion of each bolt is a securing nut 5, said nuts being fitted so as to alternate on opposite sides of the rail joint.

By reference to Fig. 5 it will be perceived 75 that each of the clamping or splice bars 2 is formed with an upper enlarged or headed portion 6, so formed as to rest snugly into contact with the lower surface of the head or tread of the track rails, and a lower enlarged or headed portion 7 adapted to clamp against the rail base, and formed of substantially the same contour and shape as said upper portion 6, which formation of the clamping or splice bars permits them to 80 be readily reversed when unduly worn at the top portion 8, which normally rests in contact with the head of the rail, where the wear usually occurs, the reversal of the bar thus causing the worn surface 8 of each bar 85 to assume the position 9, shown at the base portion of the rail, and the upper portion 10 of each bar to assume the position shown at 11 in contact with the base of the rail, thereby doubly increasing the longevity of the 90 joint. Each of the rail clamping or splice bars is located a suitable distance from the web of the track rails in order that they

may be readily adjusted inwardly by tightening up the securing nuts, thereby causing the bars to be flexed tightly into contact with the lower face of the rail head to fully 5 compensate for the wear.

It will be readily perceived by reference to Figs. 3 and 4 that we have provided a novel and peculiarly constructed locking plate 12 preferably formed from heat treated 10 spring steel usually employed for like purposes, which plate is adapted to overlap the meeting ends of the rails, and is firmly secured under high tension in contact with the outer face of each of the clamping or 15 splice bars 2 by the two securing bolts and nuts disposed nearest the meeting ends of the track rails, each locking plate 12 being formed with an inwardly bent or curved central portion 13 adapted to tightly contact the outer face of the splice bar, said 20 central portion being provided with an outwardly extended strengthening and reinforcing rib 14, and each side of the central portion of the locking plate 12 is formed 25 with a reversibly inclined twist 14' extending from its central portion to each outer end portion, with each outer end portion terminating with an inward extension 15 adapted to tightly contact with the outer 30 face of the clamping or splice bar 2.

It will be clearly evident that when the twisted locking plate 12, such as clearly shown in Fig. 3 of the drawings, is firmly secured in contact with the rail clamping or 35 splice bars 2, that by proper adjustment of the securing nuts the twist at each side of the central portion of the locking plate will force the plate to assume a straight flattened out position, with each inward extension 15 and its central portion 13 tightly in contact 40 with the splice bars under high tension, thereby securely locking the nuts to the threaded ends of the bolts and preventing the accidental loosening to the said nuts 45 usually caused by the excessive jarring which emanates from the rolling stock passing over the joints, and at the same time forming a cushioning effect of the plate between its central portion and its outer ends, 50 as clearly shown in Fig. 4 of the drawings.

By the use of this particular construction of locking plate it will be evident that the bonding wires commonly employed in connection with railway joints may be dispensed 55 with, since it will be readily seen that the rail joint at the middle portion thereof will always be retained in positive contact with the track rails thereby insuring that the electrical current will be transmitted from one 60 rail to the other, for the reason that the high tension under which this locking plate is normally secured to the rail joint insures the joint from being accidentally loosened by expansion and contraction.

It will also be understood that in the event

that the splice bar should become accidentally broken, this construction of locking plate will readily hold and retain the rails in proper alinement, until the break is discovered and repaired, thus preventing what 70 is known as "lipping" of the track rails which is liable to cause a derailment of the rolling stock.

Having thus described our invention what we claim and desire to secure by Letters 75 Patent is:—

1. A rail joint locking plate formed with an inwardly extended portion, and a twisted portion at each side of said inwardly extended portion.

2. A rail joint locking plate formed with an inwardly extended curved middle portion, and a twisted portion at each side of said middle portion.

3. A rail joint locking plate formed with an inwardly extended central portion, and the ends of the plate being reversely twisted with relation to each other.

4. A rail joint locking plate formed with an inwardly extended curved central portion, and the ends of the plate being reversely twisted with relation to each other at each side of said central portion terminating at each end with an inward extension.

5. A rail joint locking plate formed with an inwardly bent central portion, the ends of the plate being reversely twisted at each side of said central portion, and an inward extension at each end.

6. A rail joint locking plate formed with an inwardly bent central portion provided with a strengthening rib, the ends of the plate being reversely twisted at each side of said central portion, and an inward extension at each end thereof.

7. A rail joint locking plate formed with an inwardly curved central portion provided with a strengthening rib, each end of said plate being reversely twisted with relation to the other, and an elongated recess formed 110 in its inner face.

8. A rail joint lock comprising track rails, splice bars secured to said rails, a locking plate secured to the outer face of each splice bar, said locking plate being formed with an inwardly curved portion and a twisted portion at each side of said central portion, and means for securing said splice bars and locking plate to the track rails.

9. A rail joint lock comprising track rails, splice bars secured to said rails, a locking plate secured to outer face of each splice bar, said locking plate being formed with an inwardly bent central portion and each end portion being reversely twisted with reference to the other, and means for securing said locking plate in a flattened condition and with a cushioning effect near each end of said plate.

10. A rail joint lock comprising track 120

rails, splice bars secured to said rails, a locking plate secured to the outer face of each splice bar, said locking plate being formed with an inwardly curved central portion 5 provided with a strengthening rib and each end portion being reversely twisted with reference to the other terminating with an inward extension, and means for securing the plate in untwisted position into contact with the splice bar with a cushioning effect 10 near each end thereof.

JACOB A. HYLE.
ROBERT A. THOMANN.
